(57) **CLAIM**

The ornamental design for a stand for light emitting hands free device, as shown and described.

DESCRIPTION

FIG. 1 is a front perspective view of a stand for a light emitting hands free device;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines shown in the drawings illustrate portions of the stand for light emitting hands free device that form no part of the claimed design.

1 Claim, 5 Drawing Sheets
